UNITED STATES PATENT OFFICE.

GEORGE P. R. CLARK, OF OAKLAND, CALIFORNIA, ASSIGNOR TO NATIONAL ADVERTISING COMPANY, OF SAN FRANCISCO, CALIFORNIA, A CORPORATION OF CALIFORNIA.

DISPLAY APPARATUS.

Application filed January 24, 1921. Serial No. 439,505.

My invention relates to an apparatus in which a plurality of curtains having advertising matter etc. thereon are each arranged to be successively placed in display position and withdrawn therefrom.

An object of the invention is to provide a display apparatus of the type described in which each curtain when on display may be viewed from opposite sides of the machine.

Another object of the invention is to provide means for effecting the unwinding and rewinding of the curtains without the aid of springs.

A further object of the invention is to provide automatically operating means for producing different illuminating effects in accordance with the positions of the curtains.

A still further object is to provide an apparatus which is extremely simple in operation and in which the removable parts may be readily withdrawn or replaced.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a side elevation of the apparatus, portions thereof being broken away to disclose the construction more clearly.

Figure 2 is a side elevation partly in section of one end of the apparatus.

Figure 3 is an end view of the apparatus as viewed from the left of Figures 1 or 2, the end of the casing being removed to disclose the hidden structure.

Figures 4 and 5 are vertical transverse sections of the apparatus taken on the lines 4-4 and 5-5 respectively, of Figure 2.

Figure 6 is an end view of the apparatus similar to Figure 3, as viewed from the right of Figure 1.

Figure 7 is a perspective view of one of the parts of the reciprocating traveler as used in the present apparatus.

Figure 8 is a transverse sectional view of one of the rollers.

Briefly expressed the apparatus as here

shown comprises a frame and a casing having openings at their opposite sides at the upper and lower ends of which are mounted rotatable magazines containing a plurality of display curtains wound upon rollers. The 60 rollers are removably held in radially disposed recesses formed in the magazines, the recesses being adapted to register with a guideway which extends from one magazine to the other. A traveler reciprocatively 65 mounted for movement across the openings is arranged in its extreme end positions to alternately engage each magazine so that a roller upon the forward movement of the traveler may be drawn into the guideway 70 and the curtain associated therewith unwound and displayed in said openings, the return movement of the traveler enabling the curtain to be rewound and the roller replaced in the magazine. An endless member 75 moving around and concealed from the display area afforded by the openings, is arranged to impart the necessary reciprocative movement to the traveler; and when the traveler has been moved to engage a magazine, the endless member in cooperation with mechanism associated with the magazine effects such rotation of the magazine as will cause the roller and curtain already displayed and engaged by the traveler to be 80 disengaged therefrom and a new roller and curtain placed in engagement for reciprocation therewith. The traveler is so formed 85 and cooperates with the magazines and rollers in such manner that while one curtain is being drawn into display position from one magazine, another curtain from another magazine is being withdrawn from display position. Simple positive means are provided without the aid of a spring for 90 causing the rollers to rotate when they reciprocate with the traveler so that the proper unwinding or rewinding of the curtain upon the roller will always be assured. Means are also included for effectively concealing both 100 sides of the traveler and adjacent portions of the curtains as they traverse the display area thereby rendering the unwinding and rewinding of the curtains invisible. The rollers are readily detachable both from the 105 magazine and curtain thus permitting of ready replacement of the various associated parts when necessary. Automatic means are also provided for causing the curtains to be illuminated in one fashion when a curtain is 110

on full display, and for illuminating the curtains in another fashion when they are being unwound or rewound.

A detailed description follows:

5 The apparatus as here illustrated comprises a frame 2 which includes longitudinal members 3 and 4, and cross members 6 and 7, between which is provided the central opening 8. The frame is enclosed by a suitable 10 casing 9 having its opposite sides 12 and 13 hingedly mounted and provided with openings 14 and 15 respectively, disposed opposite the frame opening 8.

Arranged in the frame adjacent the upper and lower ends 17 and 18 thereof are rotatable magazines 21 and 22 respectively, in which engage a plurality of flexible curtains 23 having advertising matter or the like preferably delineated on both sides thereof.

20 Each magazine is provided with a pair of disks 24 which are fixed on shafts 26 suitably mounted in the frame. The disks are provided on the periphery thereof with radially disposed depressions or recesses 27 25 in which are adapted to be removably seated the rollers 28 on which the curtains 23 are wound as is clearly shown in Figure 5. The rollers with the exception of those happening to be positioned lowermost and uppermost in the magazines 21 and 22 respectively, are confined in their respective recesses by means of open retaining rings 29 and 30 fixed to the frame and against which the ends 36 of the rollers in the magazines 21 30 and 22 respectively abut. Each ring is provided with hinged segments 31 which may be swung outwardly in order to permit the removal or introduction of any of the rollers and curtains. Arranged at each end of

35 the frame and extending from the disks of one magazine to the disks of the other are guideways 32 and 33 with which the recesses of the respective disks are arranged to successively register so that the curtain 40 roller of the aligned recess may be withdrawn therefrom and drawn into the guideway to cause the curtain associated with the roller to be displayed in the central opening of the apparatus, or reversely to withdraw the roller from the guideways and the curtain from the opening and replace them in the magazine, all of which will be explained more fully hereinafter.

As will be clear from Figures 2 and 5, 55 the rollers 28 are formed of tubes 34 suitably fixed to hollow caps 35 which support the tubes when the roller is in the guideway as well as in the magazine. Removably held within each roller is a curtain rod 37 60 which is detachably secured to the end 38 of the curtain which extends into the roller through a slot 39 formed in and extending longitudinally of the tube. The other end 41 of the curtain is detachably secured to a 65 second curtain rod 42 which is fixed to the

disk. Associated with each roller and engaging in a slot 43 in the disks is a spring actuated tightener 44 which functions to retain the curtain tightly wound on its roller or taut when unwound therefrom.

70 Means are provided, as hereinbefore mentioned, which function when a recess of a disk is aligned with the guideway, for withdrawing a roller from such recess and drawing it into the guideway, or reversely for withdrawing the roller from the guideway and replacing it in the recess. In the present form of the apparatus the foregoing means are arranged to cooperate with each

magazine so while one roller is being withdrawn from one magazine another is being correspondingly returned to the other magazine.

Arranged to reciprocate from one magazine to the other is a traveler 46 extending across the apparatus and provided at

80 its extremities with heads 47 and 48 preferably slidably engaged in the guideways 32 and 33 respectively. Each head as here shown is provided with two vertically spaced

seats 51 and 52 open on the inner side and adapted to engage the rollers of the magazines 21 and 22 respectively.

When the traveler is in one of its extreme end positions, the seats associated with the magazine with which the traveler is then cooperating, lie in the cylindrical path defined by the rollers as they rotate in the magazine; in this manner in said position of the traveler the functioning of mechanism associated with the magazine for causing it to be rotated to successively position the disk recesses in alignment with the guideways, causes a roller already engaged in the seats to exit therefrom and be retained in the

90 magazine and enable a new roller to enter said seats whereby it may accompany the traveler as it recedes from the magazine; assuming now that a roller is already engaged in the other seat, as soon as the head

95 engages the other magazine said roller may be deposited therein and a new roller withdrawn, the continuation of which latter withdrawal movement will enable the head to return to said first magazine, deposit

100 therein the roller belonging thereto and withdraw another roller, and so on.

105 Means are also provided for causing the rollers to rotate while they are reciprocated by the traveler, whereby the curtains associated therewith will unwind and rewind independent of the action of the curtain or any spring actuated means.

Arranged in juxtaposition with the guideways and disk recesses are racks 53 and 54 respectively which are adapted to be engaged by gears 55 fixed to the rollers. Each rack

110 53 is fixed solidly to the frame, whereas the racks 54 are fixed to the disks. When the guideways and a particular set of recesses

115 are aligned, the racks 53 will also be in

aligned relation with the racks 54 associated with said recesses, thereby enabling the gears 55 to readily pass from mesh with one rack to the other. With the use of gears 5 and racks as outlined in the foregoing the curtains will be caused to positively unwind or rewind in accordance with the direction of movement of the traveler.

Means are provided for concealing the traveler and adjacent mechanism as they traverse the main opening. Arranged on opposite sides of the traveler and of sufficient size to cover both of the rollers and the adjacent portions of the associated curtains are shields 56 and 60 pivotally secured to the traveler and arranged to press inwardly against the curtain through the agency of springs 65. When the traveler is engaged with a magazine and the latter is rotated the shields adjacent said magazine should be positioned or movably mounted so as not to interfere with the curtains during the rotation of the magazine. Since the rollers in proximity to the shield 60 move toward the right said shield owing to its yielding mounting will not interfere with the rotation of the magazine. However, the shield 56 swings outwardly opposite to the direction of the shield 60. Provision has therefore been made for causing the shield 56 to swing outwardly before the traveler has reached an extreme end position. As here shown the outer ends of the shields 56 are curved outwardly and are adapted to engage fixed stops 70 adjacent each magazine so that said shield will be swung clear of and in no way will interfere with the magazine.

Means are further included for effecting the reciprocation of the traveler, the rotation of the magazines, and the proper co-operation of the movement of one with respect to the other. Suitably mounted upon idlers 57 arranged adjacent the junctures of the longitudinal and cross members of the frame, is an endless member here shown in the form of a chain 58 which is adapted to travel within the casing beyond the edges of the central opening. The chain is driven by a sprocket wheel 59 whose shaft 61 is adapted to be rotated continuously preferably at a comparatively slow rate of speed so that the curtains may be displayed for a reasonable period of time. The chain at opposite edges of the apparatus is arranged to move in proximity to the respective heads of the traveler, which heads are extended to form a yoke 62 at their outer faces so as to straddle the chain. The yoke portion of each head is provided with a shoulder 63 which is arranged to be engaged by a pin 64 or similar element fixed to the chain, the pin being enabled to enter and exit from the recess defining the shoulder, owing to the reversely disposed angular paths traversed by the chain as it enters or leaves a head in the ex-

treme end positions of the traveler. The pin is adapted to alternately engage each head and remain in engagement therewith for such period as will enable the traveler to be moved from one extreme position to another, and since the chain travels in different directions at the opposite edges of the apparatus, a reciprocative movement will thus be imparted to the traveler. The weight of the reciprocating structure is counterbalanced by a weight 66 slidably carried, as shown in Figure 1, at one end of a chain 67 which passes over suitable idler sprockets at the top of the frame and is secured at its other end to the head 47 by means of a pin 50 which is indicated in Figures 2 and 3. Secured to each head is a spring 68 having fingers 69—71 at the upper and lower ends thereof which are adapted to respectively engage stops 72 and 73 at the upper and lower ends of the frame whereby the traveler will be yieldingly retained in either of its extreme end positions and prevented from moving therefrom unless actuated by the pin 64 in the regular manner. The means for effecting the rotation of the magazines in the manner previously described, comprises in combination with the chain 58 and pin 64 etc., rotatable disks 74 and 75 fixed to shafts 76 connected by suitable gearing to the shafts 26 of the magazines. The disks 74 and connected gearing are associated with the magazine 21 and are arranged at one end thereof, whereas the disks 75 and connected gearing are associated with the magazine 22 and are disposed at the end thereof opposite to that on which the disks 74 are arranged relative to the magazine 21. The chain 58 rides upon a roller 77 loosely mounted between the disks on the shaft 76, and each disk is provided with diametrically opposed openings 78 which are normally disposed in vertical alignment as shown in Figures 1 and 2. The openings 78 are arranged to be engaged by the pin 64 to effect a half turn of the disks 74 and 75, which turn produces such rotation of the magazine as will move a new roller into position for engagement with the traveler. Each of the magazines are preferably provided with cams 79 formed with depressions 80 corresponding in number and position to the recesses 27. The depressions are arranged to be engaged by spring pressed rollers 81 so that the proper amount of the periodical rotation of the magazines is assured.

Automatically operated means are provided for causing the curtains when in full display position to be brightly illuminated and for causing them to be more or less dimly illuminated or some such different characteristic when the traveler is in motion. As here shown a suitable electric switch 82 is fixed to the frame and controls the various branches 83 and 84 of a circuit

85 provided with lights 87 and 88 respectively. I have found that by using colored lights, such as red ones, for the branch 84, which effects the illumination of the curtains 5 when not in full display, and plain lights for the branch 83 which causes the curtains to be illuminated when in full display, the desired effective contrasts are secured. The switch is arranged to be actuated by the head 10 of the traveler as it reciprocates between the magazines. Disposed in proximity to the magazines 21 and 22 are levers 91 and 92 respectively, conveniently mounted on the shafts 94 of two of the pulleys 57. The 15 levers are connected to each other by means of links 95 and lever 96, the latter being in turn connected by a link 97 to the switch lever 98. One arm of the lever 96 is secured to a spring 93 so as to cause the switch lever 20 98 to normally close the branch circuit 83. Fixed to the inner ends of the levers 91 and 92 are projections 99 one of which is adapted to be engaged by the beveled face 100 of the head 47 when the traveler assumes either 25 of its extreme end positions, engagement of the face 100 with either of said projections serving to rock levers 91 and 92 and thereby move the switch lever 98 to open the branch 83 and close the branch 84. In this manner 30 the curtain when on display will be brilliantly illuminated. As soon as the traveler withdraws from a magazine and the face 100 becomes released from the projection the switch lever due to the spring 93 opens the 35 branch 83 and closes the branch 84.

The operation of the apparatus is as follows:

Assuming as shown in Figures 2, 3, 4, and 5 that the traveler has just reached its lowermost position so that both heads 47 and 48 engage the lower magazine 22, the curtain 23^a of the upper magazine 21 is fully displayed since its end 41 is fixed to the latter magazine, and its roller 28^a is engaged in the 40 seats 51 of the heads, however the curtain 23^b whose roller 28^b engages in the seats 52, has already been displayed and is replaced in its recess in the disks 74. By referring particularly to Figure 2 it will be noted that 45 the pin 64 of the chain 58 has just left the shoulder 63 of the head 47 and is about to enter the opening 78 of disks 74. Upon entering said opening the continued movement of the pin causes the disks 74 and its 50 shaft 76 to rotate a half of a revolution thereby causing the magazine 22 to rotate sufficiently to move the roller 28^b out of the seat 52 and move a new roller 28^c into said seat. After disengaging itself from the 55 disk 74 the pin moves across the bottom of the apparatus and then up the right edge thereof to engage the shoulder 63 of the head 48, during which movement of the pin the curtain 23^a is still on display and brightly 60 illuminated. As soon as the pin 64 engages 65

the head, the traveler begins its upward course causing the curtain 23^a to begin rewinding on its roller and causing the roller 28^c to move with it to effect the unrolling of the curtain 23^b. At the same time the circuit 70 83 is opened and the circuit 84 closed. Upon raising the traveler to its uppermost position, at which time the curtain 23^b is on full display and subjected to the full illumination afforded by the circuit 84, the pin 64 75 engages the disk 75, and thereafter substantially the same operations are undergone in connection with the curtains 23^b and 23^a as were had with the curtains 23^a and 23^b in connection with the lower magazine 22. 80

I claim:

1. A display apparatus comprising a frame having an opening, a rotatable magazine disposed adjacent one end of said opening, a plurality of display curtains arranged to removably engage said opening, curtain rollers associated with each curtain and removably held in said magazine, a reciprocating traveler adapted to successively withdraw each roller from said magazine, a stationary member extending along the side of said opening, and means rotatable with said roller arranged to engage said stationary member whereby the roller will be caused to rotate as it moves with the traveler. 95

2. A display apparatus, comprising a frame, a rotatable magazine disposed adjacent one end thereof, a plurality of display curtains and associated rollers arranged in said magazine, a reciprocating traveler 100 adapted to successively engage each roller and arranged to withdraw it from and replace it in said magazine, a gear fixed to each roller, and a rack arranged to cooperate with said gears whereby the roller engaged in said traveler will be caused to rotate during the reciprocation of the traveler. 105

3. A display apparatus, comprising a frame, a rotatable magazine disposed adjacent one end thereof, a plurality of display 110 curtains and associated rollers removably held in said magazine, a traveler adapted to successively engage each of said rollers and arranged to withdraw them from and replace them in said magazine, a gear fixed to each roller, a rack fixed in said frame and arranged to be engaged by each of said gears when the associated roller is engaged with said traveler and means for retaining each roller and associated curtain in predetermined position on said magazine. 115

4. A display apparatus, comprising a frame, a rotatable magazine disposed adjacent one end thereof, a plurality of display curtains and associated rollers removably held in said magazine, a reciprocating traveler movable toward and from said magazine adapted to successively engage each of said rollers and withdraw them from and replace them in said magazine, a gear 125 130

fixed to each roller, a rack fixed in said frame arranged to be engaged by each of said gears when the associated roller is engaged with the traveler, a second rack cooperating with each of said gears and fixed to said magazine, and means for retaining said rollers in said magazine.

5. A display apparatus comprising a frame, a rotatable magazine adjacent one end thereof, a plurality of rollers removably positioned in said magazine and adapted to traverse a common circular path, display curtains wound on said rollers, a traveler reciprocatively mounted for movement toward and from said magazine, a seat formed in said traveler arranged to lie in said path of the rollers during the rotation of said magazine whereby each roller may successively enter said seat and reciprocate with the traveler and exit from the seat after partaking of said movement, guides between which said rollers are held against lateral displacement during the reciprocative movement thereof, a gear associated with each roller, and a rack cooperating with said gears arranged to effect the rotation of said rollers during the reciprocative movement thereof whereby said curtains may be unwound from or rewound on the rollers.

30. 6. A display apparatus comprising a frame, a rotatable magazine adjacent each end thereof, a plurality of curtain rollers removably positioned in each magazine and adapted to respectively traverse a common cylindrical path, display curtains associated with said rollers, a traveler reciprocatively mounted between said magazines, a seat adjacent each end of said traveler adapted to cooperate with the adjacent group of rollers and arranged to lie in the said path of the associated group of rollers during the rotation of the associated magazine whereby each associated roller may successively enter the seat and reciprocate with the traveler and exit from the seat after said movement, guides between which the rollers are held against lateral displacement during said reciprocative movement, a gear associated with each roller, and a rack extending the length of said guides and arranged to cooperate with said gears to effect the rotation of said rollers during reciprocative movement thereof whereby said curtains may be unwound from or rewound on the rollers.

55. 7. A display apparatus comprising a frame, a magazine mounted in said frame, one or more curtain rollers removably positioned in said magazine and arranged to be reciprocated perpendicularly with respect thereto, a curtain wound upon said roller and having one end thereof fixed to the roller and the other fixed to the magazine, cooperating members provided on said roller and fixed solidly to said frame

adapted to cause the rotation of the roller as it is reciprocated whereby said curtain may be unwound from or rewound upon the roller, and means for subjecting said curtain to a yielding tension.

70

8. A display apparatus comprising a frame, a magazine rotatably mounted therein, one or more hollow curtain rollers removably positioned in said magazine and provided with a longitudinally extending slot, a removable curtain rod arranged within said roller, a second curtain rod fixed to said magazine and arranged outside of said roller, a curtain adapted to be wound on said roller and having one end thereof extending through said slot and fixed to said inner rod and having its other end fixed to said outer rod, and a spring pressed curtain tightening rod arranged intermediate the ends of said curtain.

85

9. A display apparatus comprising a frame, a magazine rotatably mounted adjacent one end thereof and provided with radial recesses at their outer ends, curtain rollers arranged to engage in said recesses, a fixed annular track for retaining said rollers in said recesses during the rotation of the magazine, having an opening, a guideway perpendicularly disposed with respect to the axis of rotation of the magazine, and aligned with said track opening, means for rotating said magazine to successively align each of said recesses with said guideway, a reciprocating traveler movable in said guideway and arranged to remain stationary and lie in the path of said rollers during the rotation of said magazine whereby one of said rollers may become engaged with or disengaged from the traveler.

90

10. A display apparatus comprising a frame having an opening, a rotatable magazine adjacent an end of said opening, a plurality of wound display curtains arranged in said magazine, a traveler mounted for reciprocation to and from said magazine and adapted to effect the unwinding or rewinding of said curtains whereby they may be displayed in or removed from said opening, an endless movable member surrounding the area defined by said opening, and means on said member for alternately moving said traveler and rotating said magazines.

100

11. A display apparatus comprising a frame having an opening therein, a rotatable magazine adjacent each end of said opening, a plurality of roller display curtains arranged in said magazines, a reciprocating traveler extending across said opening and arranged to successively engage said curtains whereby they may be unwound and rewound so as to be displayed in and removed from said opening, an endless movable member surrounding said opening, means for imparting continuous motion to said endless member, means on said member

110

115

120

125

130

- arranged to alternately engage the opposite ends of said traveler to effect the reciprocation thereof, and means associated with said magazines adapted to cooperate with said traveler moving means whereby each of said magazines will be alternately rotated so as to successively present said curtains in position for engagement with or disengagement from said traveler.
- 10 12. A display apparatus comprising a frame having an opening, a rotatable magazine adjacent each end of said opening, a plurality of roller display curtains arranged in said magazines, a reciprocating traveler 15 extending across said opening and arranged to engage said curtains whereby they may be unwound and rewound so as to be successively displayed in and removed from said opening, an endless chain adapted to move continuously around said opening, a pin on 20 said chain adapted to alternately engage the opposite ends of said traveler to effect the reciprocation thereof, a rotatable member associated with each magazine and arranged 25 to be engaged by said pin after said traveler has been moved into engagement with

the magazine associated with said rotatable member whereby said magazine will be rotated sufficiently to enable the displayed curtain to be disengaged from the traveler and an undisplayed curtain to be engaged therewith. 30

13. A display apparatus comprising a frame having an opening, a group of display curtains arranged adjacent each end of 35 said opening, a traveler adapted to reciprocate between said groups and to successively engage said curtains whereby they may be displayed in and removed from said opening, sources of electrical illumination and 40 circuits therefor; and a switch for opening and closing each of said circuits and adapted to be actuated by said traveler during the reciprocation thereof whereby one of said circuits will be closed when one of said curtains is in full display in said opening and the other circuit will be closed when none of said curtains are in full display. 45

In testimony whereof, I have hereunto set my hand at Oakland, California, this 31st day of December, 1920.

GEORGE P. R. CLARK.
